(57) **CLAIM**

The ornamental design for a vehicle mirror, as shown and described.

DESCRIPTION

FIG. 1 is a top, front, and left side perspective view of a left vehicle mirror, showing our new design; FIG. 2 is a rear elevational view thereof; FIG. 3 is a right side elevational view thereof; FIG. 4 is a top plan view thereof; FIG. 5 is a top, rear, and right side perspective view thereof; FIG. 6 is a bottom plan view thereof; and, FIG. 7 is a bottom, front, and left side perspective view thereof.

The broken lines illustrate portions of the vehicle mirror that form no part of the claimed design.
